US0D1092386S

(12) **United States Design Patent** (10) Patent No.: **US D1,092,386 S**
(45) Date of Patent: ** Sep. 9, 2025

(54) **WIRELESS CHARGER**

(71) Applicant: **Xiaozhong Cai**, Guangdong (CN)

(72) Inventor: **Xiaozhong Cai**, Guangdong (CN)

(73) Assignee: **SHENZHEN YOULIFANG DA TECHNOLOGY CO LIMITED**, Shenzhen (CN)

(**) Term: **15 Years**

(21) Appl. No.: **29/891,515**

(22) Filed: **May 7, 2023**

(30) **Foreign Application Priority Data**

Nov. 11, 2022 (CN) 202230755199.4

(51) **LOC (15) Cl.** **13-02**

(52) **U.S. Cl.**
USPC **D13/108**

(57) **CLAIM**

The ornamental design for a wireless charger as shown and described.

DESCRIPTION

FIG. 1 is a perspective view of a wireless charger showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom side perspective view thereof.

The broken lines in the drawings depict portions of the wireless charger that form no part of the claimed design.

1 Claim, 8 Drawing Sheets
